FOREIGN PATENT DOCUMENTS

(73) Assignee: **OPTINOSE AS**, Oslo (NO)WO WO 96/22802 8/1996
WO WO 98/53869 12/1998
(Continued)(**) Term: **15 Years**(21) Appl. No.: **29/567,592**

Primary Examiner — Wan Laymon

(22) Filed: **Jun. 10, 2016**

Assistant Examiner — Mark Booker

Related U.S. Application Data

(74) Attorney, Agent, or Firm — Finnegan, Henderson, Farabow, Garrett & Dunner, LLP

(63) Continuation of application No. 29/455,733, filed on May 23, 2013, now Pat. No. Des. 761,951.

CLAIM(51) **LOC (11) Cl.** **29-02**

I claim the ornamental design for a nosepiece unit, as shown and described.

(52) **U.S. Cl.****DESCRIPTION**(58) **Field of Classification Search**

FIG. 1 is a front, top perspective view of a first embodiment of a nosepiece unit showing the new design;

USPC D24/110; 128/200.13, 203.22, 203.23,

FIG. 2 is a front elevation view thereof;

128/203.24, 207.18, 202.22, 203.12,
128/203.15, 203.21, 204.11, 204.12,
128/200.14, 200.23, 200.24, 201.23,
128/201.28, 203.18, 203.29

FIG. 3 is a rear elevation view thereof;

CPC .. A61M 15/08; A61M 11/00; A61M 15/0021;
A61M 15/085; A61M 15/0098; A61M
2210/0625; A61M 15/0003; A61M
15/0015; A61M 15/002; A61M 15/0095;
A61M 11/007; A61M 11/08; A61M
15/009; A61M 2202/0468; A61M
2202/064; A61M 2205/8281

FIG. 4 is a left side view thereof;

See application file for complete search history.

FIG. 5 is a right side view thereof;

(56)

References Cited

FIG. 6 is a top plan view thereof;

U.S. PATENT DOCUMENTS

FIG. 7 is a bottom plan view thereof;

605,436 A 6/1898 Kellogg
642,748 A 2/1900 Manners
658,436 A 9/1900 Groth
746,749 A 12/1903 Seidel

FIG. 8 is a front, top perspective view of a second embodiment showing the new design;

FIG. 9 is a front elevation view thereof;

FIG. 10 is a rear elevation view thereof;

FIG. 11 is a left side view thereof;

FIG. 12 is a right side view thereof;

FIG. 13 is a top plan view thereof; and,

FIG. 14 is a bottom plan view thereof.

The broken lines of even length shown in the drawings illustrate portions of the nosepiece unit that form no part of the claimed design.
